COMBINED UMBRELLA AND SHEATH

Fritz Bremshay, 28 Wilhelmstrasse,
565 Solingen-Ohligs, Germany

Filed Nov. 3, 1969, Ser. No. 19,892

Claims priority, application Germany May 7, 1969

Term of patent 14 years

Int. Cl. D3—99

U.S. Cl. D87—1

FIG. 1 is a perspective view of the combined umbrella and sheath;

FIG. 2 is an end view of the combined umbrella and sheath shown in FIG. 1 with the handle strap removed;

FIG. 3 is an elevational view taken from the other end of the combined umbrella and sheath;

FIG. 4 is a side elevation of the combined umbrella and sheath;

FIG. 5 is a bottom plan view of the combined umbrella and sheath; and

FIG. 6 is a vertical cross section taken along lines 6—6 in FIG. 1.

I claim:

The ornamental design for a combined umbrella and sheath, as shown.
